FIG. 3.

UNITED STATES PATENT OFFICE.

PIOTR NIEWIAROWSKI AND TOMASZ HALAGARDA, OF OMAHA, NEBRASKA.

DIRECTION INDICATOR.

1,409,883.

Specification of Letters Patent. Patented Mar. 14, 1922.

Application filed February 10, 1921. Serial No. 443,911.

To all whom it may concern:

Be it known that we, (1) PIOTR NIEWIAROWSKI and (2) TOMASZ HALAGARDA, (1) a citizen of the United States of America, and (2) a citizen of Poland, residing at Omaha, in the county of Douglas and State of Nebraska, have invented certain new and useful Improvements in Direction Indicators, of which the following is a specification.

This invention relates to certain new and useful improvements in direction indicators for vehicles, and the primary object of the invention is to greatly improve the form of signal or indicator shown and described in the United States patent to Piotr Niewiarowski No. 1,353,359, September 21, 1920.

One object of the invention is to simplify the operating mechanism of signals of this character so that by the special manipulation of a single member, the indicator member may be extended and swung to the right or to the left at will.

A further object of the invention is to provide an improved construction wherein the manipulation of the operating member or handle will control circuits to illuminating means and an audible signal when the signal member is extended.

Still another object of the invention is to provide an improved guiding means for the operating member or handle for limiting movement of the latter to the proper distance when operated for swinging the signal member to the right or to the left, or when returning it to its normal intermediate position, as well as for properly limiting the movement of said member or handle when manipulated to extend the signal member when in either of its horizontally swung positions, said guiding means being constructed to engage the operating member or handle so as to normally releasably retain the signal in either of its raised positions.

Another object of the invention is to generally improve and simplify structures of this kind so that the same will be extremely simple in construction as well as durable and efficient in operation for meeting all of the requirements for a successful commercial use.

With the above general objects in view and others that will appear as the nature of the invention is better understood, the same con-

sists in the novel form, combination and arrangement of parts hereinafter more fully described, shown in the accompanying drawings and claimed.

In the drawings, wherein like reference characters indicate corresponding parts throughout the several views,

Figure 1 is a side elevational view of the device attached to an automobile and constructed in accordance with the present invention,

Figure 2 is a top plan view of the device shown in Fig. 1,

Figure 3 is a vertical sectional view of the signal, drawn on a larger scale and with parts broken away,

Figure 4 is a horizontal sectional view taken upon line IV—IV of Fig. 3, and showing the electrical circuits somewhat diagrammatically.

Figure 5 is a rear elevational view of the device shown in Fig. 3,

Figure 6 is a horizontal sectional view taken upon line VI—VI of Fig. 3, and

Figure 7 is a fragmentary side elevational view of a modified form of signal member which may be employed with the mechanism.

Referring to the drawings in detail, the numeral 5 designates a frame or casing through which extends an upright rotatably mounted tube 6, the lower end of which has a spur pinion 7 keyed thereon, the pinion 7 being arranged within the casing 5 and meshing with a relatively large spur gear 8 which is rotatably mounted in the casing 5 and which is provided with a rigid stub shaft 9 which projects downwardly through the bottom wall of the casing 5, and operating member or hand lever 10 being pivoted at its forward end as at 11 to the lower end of said stub shaft 9, for vertical swinging movement. The pinion 7 prevents downward movement of the tube 6 through the casing 5, and nuts 12 or the like are provided on the tube 6 so as to prevent upward movement of the same relative to the casing 5.

Passing through a longitudinally extending elongated slot 13 in the upper portion of tube 6, is a vertically slidable ear 14 which, in combination with the fixed lug 15, is pivotally attached to a system of simple levers, forming an extensible lazy tong arm 16 to which longitudinal movement is im-

parted by means of a tubular rod 17 which has the ear 14 fixed to the upper end thereof, and which is actuated vertically by the hand lever 10. A hand 18 for pointing direction, 5 is attached to a transverse bar or plate 19, and the latter is connected by suitable pivot pins to the outer elements of the extensible arm 16, one pivot being fixed as at 20 and the other being slidably in the slot 21 of the 10 plate 19. The handle 10 and tube 17 are normally held depressed or lowered by means of a compression spring 22 which is arranged within the tube 6 between an abutment 23 which is fixed in the upper end portion of said tube, and the upper end of the tubular rod 17, whereby the lazy tong arm 16 is normally held in collapsed condition with the hand retracted.

The tubular rod 17 has a slot rod 24 extending therethrough and fixed therein, said rod 24 being extended upwardly beyond the upper end of the rod 17 and through the spring 22 where it terminates normally in spaced relation to the central contact 25 of 25 an incandescent lamp 26 which is suitably removably fixed in the upper end of the tube 6. The rod 24 is suitably insulated as at 27 from the rod 17 and other surrounding metallic parts, and a segmental contact plate 28 is suitably fixed to the projecting lower end of the rod 24 so as to be insulated from the rod 17 and to be engaged by the arcuate plate 29 which is fixed to the hand lever 10, when the latter is in any of its 35 horizontally swung positions, whereby upward movement of said hand lever will cause simultaneous upward movement of the rods 17 and 24 when said hand lever is in any of its said positions. The shell of the 40 lamp 26 is in electrical connection with the tube 6, and also with the casing 5, one wall of which is provided with a grounded binding post 30. The binding post 30 is electrically connected by means of a wire 31 to one contact 32 of a switch, the other contact 33 of said switch being connected to one side of a battery 34 whose other side is connected by means of wire 35 with the binding post 36 of a yieldable contact arm 37 45 which is insulated from the casing 5 as at 38 and which is arranged in the path of the plate 28 so as to be engaged by the latter when the rod 17 is elevated a sufficient distance. It will thus be seen that when the 50 contact 33 is engaged with the contact 32, and the rods 17 and 24 are elevated so as to cause engagement of plate 28 with contact 37 and engagement of the upper end of rod 24 with the central lamp contact 25, a 55 circuit will be completed for lighting the lamp 26 simultaneously with the extension of the arm 16, as is desirable at night-time for illuminating the signal hand 18. The rays from the lamp 26 may be reflected to 60 toward the hand 18 by means of a suitable 65

reflecting hood 39 which is preferably detachably mounted upon the upper end of the tube 6.

Another spring contact, similar to the contact 37 and indicated at 40, is insulated from the casing 5 as at 41, and is provided with a binding post 42 which is connected by means of a wire 43 with one side of an audible signal such as horn 44, the other side of said signal being connected with the wire 31, 70 and the contact 40 being arranged with its free end portion directly above and normally in slight spaced relation to the free end portion of the contact 37. Thus, when the plate 28 is sufficiently elevated, the lamp 26 will 75 not only be lighted, but the contacts 37 and 40 will be engaged with each other for closing the circuit to the audible signal 44 and thereby calling attention of pedestrians and the like to the intended change in direction 80 indicated by the hand 18.

As shown in Fig. 7, the hand 18 may be constructed so as to offer little resistance to the wind and so as to have a conspicuous and ornamental appearance, by stamping 90 the same from sheet metal to provide numerous relatively large openings or perforations 18' therethrough and by providing the fingers with colored borders as at 45, special openings 46 being provided to have the appearance of the finger and thumb nails of the hand.

A vertical plate 47 is fixed to the rear of the casing 5 so as to project above and below the latter, and this plate is formed with a top flange 48 through which suitable fastening devices may be passed for rigidly mounting the device as indicated in Fig. 1 in front of the driver's seat sufficiently midway between the sides of the vehicle and 100 with the tube 6 extending upwardly of the wind shield A of the vehicle, the hand lever 10 being disposed adjacent the dash of the vehicle within convenient reach of the operator. The plate 47 has a substantially 110 E-shaped slot 49 formed therein, with the back portion of the E-shaped slot horizontally disposed adjacent the lower edge of the plate 47 and with the legs or arms of said slot extending upwardly. The shank of 115 the hand lever 10 projects through this slot 49, and it will thus be seen that said lever will be effectively guided and limited in movement for proper manipulation of the signal. In other words, when the lever 10 is 120 disposed in its normal position as shown in Fig. 5, the operator may raise the same to a position in the upper end of the central leg of the slot 49 for extending the hand 18 longitudinally of the vehicle so as to 125 indicate intent to keep straight ahead. The plate 47 is provided with notches 50 at the lower ends of each of the leg portions of said slots into which the lever 10 will normally automatically seat for preventing ac- 130

5 cidental horizontal swinging movement of the signal arm. Upon swinging the lever 10 to the right, said lever will cause rotation of the gear 8 toward the left and this will cause rotation of the tube 6 and signal arm 16 to the right by transmission of the motion from gear 8 to tube 6 through pinion 7. On the other hand, if the lever 10 is swung to the left, similar swinging movement 10 is imparted to the arm 16. In this way the arm may be swung either to the right or left as desired, for indicating the driver's intent to turn in either one of these directions, and as soon as the arm has been 15 swung to its desired position, it can be immediately extended by further manipulation of the same lever 10 by swinging the same upwardly. The operation of the device is thus exceedingly simplified and 20 proved as a plurality of controlling members for performing these two functions have been employed heretofore as in the above mentioned patent at 15 and 21.

It will, of course, be understood that the 25 arm 16 may be extended during the day time by simply moving the lever 10 upwardly a slight distance, without causing contact between the plate 28 and yieldable contact 30 so as to avoid lighting of the lamp 26 at such time.

As the several operations of the device and the general manner of employing the construction as a drive signal have been dealt with in describing the structure of the 35 invention, it is believed that the construction and operation of the invention as well as the advantages of the same will be readily understood and appreciated from the foregoing description by those skilled in the art.

40 What is claimed as new is:-

1. A vehicle drive signal comprising an extensible signal arm rotatably mounted for horizontal swinging movement, means including a single operating member to horizontally swing and to extend said arm, and means to prevent extension of the arm until it has been swung to a predetermined position.

2. A vehicle drive signal comprising an extensible signal arm rotatably mounted for 50 horizontal swinging movement, means including a single operating member to horizontally swing and to extend said arm, and means to prevent extension of the arm until it has been swung to a predetermined position, said last named means providing a central normal rest position and right and left rest positions at the opposite sides thereof for the operating member.

3. In a vehicle direction signal, a rotatable 55 upright member, an extensible signal arm carried by and rotatable with said upright member, a vertically movable element carried by the rotatable member and operatively connected to the extensible arm so as to cause the latter to extend upon sliding

movement of said element, and a single lever operatively connected to the rotatable upright member and operatively associated with the sliding element whereby horizontal swinging movement of the lever will cause 70 horizontal swinging movement of said extensible arm, and whereby vertical swinging movement of said lever will cause sliding of the slidable element for extending said arm.

4. In a vehicle direction signal, a rotatable 75 upright member, an extensible signal arm carried by and rotatable with said upright member, a vertically movable element carried by the rotatable member and operatively connected to the extensible arm 80 so as to cause the latter to extend upon sliding movement of said element, a single lever operatively connected to the rotatable upright member and operatively associated with the sliding element whereby horizontal 85 swinging movement of the lever will cause horizontal swinging movement of said extensible arm, whereby vertical swinging movement of said lever will cause sliding of the slidable element for extending said arm, and means to prevent accidental swinging 90 movement of the lever when the extensible arm is collapsed.

5. In a vehicle direction signal, a rotatable 95 upright member, an extensible signal arm carried by and rotatable with said upright member, a vertically movable element carried by the rotatable member and operatively connected to the extensible arm so as to cause the latter to extend upon sliding 100 movement of said element, a single lever operatively connected to the rotatable upright member and operatively associated with the sliding element whereby horizontal 105 swinging movement of the lever will cause horizontal swinging movement of said extensible arm, whereby vertical swinging movement of said lever will cause sliding of the slidable element for extending said arm, and means to prevent accidental swinging 110 movement of the lever when the extensible arm is collapsed and when said lever is in either of three predetermined different horizontally swung positions.

6. In a vehicle direction signal, a rotatable 115 upright member, an extensible signal arm carried by and rotatable with said upright member, a vertically movable element carried by the rotatable member and operatively connected to the extensible arm so as to cause the latter to extend upon sliding 120 movement of said element, a single lever operatively connected to the rotatable upright member and operatively associated with the sliding element whereby horizontal swinging 125 movement of the lever will cause horizontal swinging movement of said extensible arm, whereby vertical swinging movement of said lever will cause sliding of the slidable element for extending said arm, means to pre- 130

vent accidental swinging movement of the lever when the extensible arm is collapsed and when said lever is in either of three predetermined different horizontally swung positions, and means to prevent vertical swinging movement of the lever except when the lever is in said predetermined positions.

In testimony whereof we affix our signatures in presence of two witnesses.
